UNITED STATES PATENT OFFICE.

JOHN BEISWANGER, OF STEUBENVILLE, OHIO, ASSIGNOR TO GILL BROTHERS COMPANY, OF STEUBENVILLE, OHIO, A CORPORATION OF WEST VIRGINIA.

DESIGN FOR A UTILITY-TRAY.

56,335.

Specification for Design.

Patented Oct. 5, 1920.

Application filed October 31, 1919. Serial No. 334,858. Term of patent 7 years.

To all whom it may concern:

Be it known that I, JOHN BEISWANGER, a citizen of the United States of America, and resident of Steubenville, county of Jefferson, State of Ohio, have invented a certain new, original, and ornamental Design for a Utility-Tray, of which the following is a specification.

In the accompanying drawing I have illustrated a utility tray, constructed in accordance with my invention, the same being of resistive transparent glass.

In the drawing, Figure 1 is a bottom plan view of a utility tray showing my invention.

Fig. 2 is a perspective view looking into the dish.

Having thus described and illustrated my invention, I claim:

The ornamental design for a utility tray substantially as shown.

Signed by me at Steubenville, Jefferson county, Ohio, this 22nd day of October, 1919.

JOHN BEISWANGER.
